UNITED STATES PATENT OFFICE.

JOHN R. BYRNE, OF SCHENECTADY, NEW YORK, ASSIGNOR TO GENERAL ELECTRIC COMPANY, A CORPORATION OF NEW YORK.

SWITCH.

1,190,103.

Specification of Letters Patent.

Patented July 4, 1916.

Application filed November 12, 1913. Serial No. 800,449.

To all whom it may concern:

Be it known, that I, JOHN R. BYRNE, a citizen of the United States, residing at Schenectady, county of Schenectady, State 5 of New York, have invented certain new and useful Improvements in Switches, of which the following is a specification.

The present invention relates to electric switches and more especially to switches 10 operating to open and close an electric circuit with a snap action.

The switches formerly in use in sockets for incandescent lamps were required to make and break currents of only an ampere 15 or less and accordingly were able to perform their functions without destruction by arcing of the current even though they did not operate with a snap action, and so long as the sockets were used for supplying current 20 to lamps only they gave no trouble. However, in recent years, the practice has grown up of connecting to the ordinary lamp socket electric heaters, fans, motor and other current consuming devices requiring

25 several amperes current, and as a consequence there is at the present time a strong demand for lamp sockets having switches capable of successfully closing and opening circuits carrying several amperes current.

30 It has long been recognized that on account of the necessarily small dimensions and consequent frailty of the parts of a switch located in a lamp socket that the switch should be capable of being freely turned in both 35 directions. Moreover, a switch operable on a quarter turn possesses many advantages over a switch requiring a half turn to operate it since there are many positions in which the switch cannot readily be given a 40 half turn by the hand. A quarter turn switch possesses the added advantage that the handle or thumb piece automatically indicates the on and off positions of the switch.

45 One object of my invention is to provide an improved form of electric switch which shall operate with a snap action upon turning the actuating member a quarter turn in either direction, and which shall be strong 50 and durable when of small dimensions.

Another object of my invention is the provision of a novel form of stop for the switch, which is certain in its action in arresting the rotation of the switch after it has accomplished a quarter turn movement in either

direction and which is well adapted to stand the sudden impacts to which it is subjected without prematurely wearing out.

For a fuller understanding of my invention, reference may be had to the accompanying drawings illustrating one embodiment thereof, in which—

Figure 1 is a longitudinal section, with the lower half of the insulating base in elevation, of a lamp socket in which a 60 switch embodying my invention is located; Fig. 2 is a plan view of the lower part of the supporting base with the switch mounted on the base; Fig. 3 is a side elevation of the switch; Fig. 4 is a plan view of Fig. 3, 70 but showing the operating handle angularly displaced with reference to the switch, thus placing the operating parts of the switch under tension; Fig. 5 is a longitudinal section of the switch and the support for the 75 same; Fig. 6 is a perspective view thereof with parts broken away; Fig. 7 is a plan view of an automobile lighting switch embodying my invention, and Fig. 8 is a section taken on the line 8—8, Fig. 7.

Referring to the drawings, and first to Figs. 1 to 6, 1 is the lower half of a lamp socket supporting base made of any suitable insulating material, such as molded porcelain, and 2 is the upper half thereof.

85 The lower half of the base is formed with a transverse recess 3, with which a recess 4 in the upper half registers, the two recesses forming a housing for the operating parts of the switch. The supporting base 90 is inclosed in a lamp socket shell 5 of usual construction provided with a cap 6. A base plate or yoke A, which is formed to fit in the bottom of the recess 3, is provided with up-turned ends 7 and 8 which constitute 95 supporting brackets for the operating parts of the switch. The bottom part of the base plate is also provided with upwardly and inwardly extending lugs 9 having notches 10 at their ends as indicated in Fig. 6. The up-turned end 8 of the base plate is also provided with inwardly turned lugs 8a which embrace and secure in position the ends of two flat spaced springs 11, the opposite ends of which extend beneath the in-turned ends of the brackets 9 and project outwardly across the notches 10, the springs extending substantially to the far edges of the brackets. The base plate A is secured 100 to the supporting base 1 by screws (not

shown in the drawing). An actuator for producing a torque in the switch comprising an actuating spindle 13, is mounted in an opening in the bracket 8 of the base 5 plate. An insulated handle 14 of the usual form is suitably secured to the outer end of the spindle 13, and the inner end is provided with laterally and forwardly extending arms 15 and 16 parallel with the spindle 10 itself and here shown as integral therewith. One end of a sleeve 17 embraces the inner end of the spindle 13, while its opposite end is mounted in the bracket 7. The sleeve is provided with a flange or collar 18 which 15 engages the inner face of the bracket 7. A rotary switch member B comprises a contact plate 20 having forwardly projecting contact blades 20^a, a detent wheel 21, shown as of the star wheel type, a disk 22 provided 20 with a rearwardly extending arm 23 and a plate 24 from which an annular piece 25 is stamped up, which constitutes a double cam facing the actuator or actuating spindle. The upper part of the cam ring 25 (as 25 viewed in Fig. 6) is cut away at 25^a to form a notch within which the arm 23 is received, the two ends of the divided cam being seated against shoulders 23^a on the arm 23. The contact plate 20, detent wheel 21 and plates 30 22 and 24 are fixedly mounted upon a sleeve 26, which is in turn loosely mounted upon the sleeve 17 and provided with a flange 27 engaging the plate 20, the end of the sleeve facing the actuator being slightly 35 turned out to hold in position the members which are mounted thereon. A coil spring 28 surrounds the end of the sleeve 17 adjacent the actuating spindle 13, the ends of the spring being bent outwardly on opposite 40 sides of the arms 16 and 23 and thus normally holding them in alinement. A collar 29 surrounding the sleeve 17 separates the spring 28 from the plate 24. A coil spring 30 surrounds the end of the sleeve 45 17 mounted in the bracket 7 and impels the member B toward the actuating spindle. Stationary binding terminals for the wires are indicated by the numerals 31 and 32, which are suitably connected to stationary contacts 33 and 34.

The operation of my device is as follows: In the normal position of the operating parts of the switch, one of the detents of the wheel 21 is located between the spaced ends 50 of the flat springs 11 which prevent movement of the wheel and of the member B in either direction, and the end of the arm 15 engages the lowest portion of the cam 25, that is, the portion of the cam adjacent to 55 the plate 24. Now, when the actuator is turned in either direction, rotary movement of the member B is prevented and the arm 16 moves away from the arm 23, thus winding the spring 28 and placing the member 60 B under tension. At the same time, the end

of the arm 15 rides up one side or the other of the cam 25, depending on the direction of movement of the actuator and moves the member B axially of the sleeve 17 against the spring 30 until the detent of the wheel 21, which has been retained between the ends of the springs 11, is moved to the left sufficiently to clear the end of the engaging spring 11, at which time a quick rotary movement of the member B is produced and 70 the contact blades 20^a of the switch element 20 quickly separated from or brought into engagement with the stationary contacts 33 and 34 to break or make the circuit. As soon as the detent is freed from one of the 80 springs 11 and the member B begins to turn, the spring 30 forces member B toward the actuator so that the next detent of the wheel rides over and depresses the other of the springs 11 and is brought to a stop between 85 the two springs after the switch has completed a movement of 90 degrees. Since the springs 11 are depressed by the detents riding over the surfaces of the springs, it will be apparent that there is little wear either 90 upon the springs or the detent wheel itself, and since the longitudinal edges of the springs engage the transverse shoulders of the detents upon arresting the movement of part B, while the end edges of the springs 95 in clearing the side shoulders of the detents control the release of the part B, it is readily seen that even though there should be more or less wear of the parts under the hammer blows incident to arrest of the switch movement, the shoulders which determine the release of the part B will be unaffected and accordingly so long as the springs and detents properly function to arrest the rotatable member B, the latter will be permanently locked and fully tensioned by the key 100 before being released.

In Figs. 7 and 8 I have shown my invention embodied in an automobile lighting switch; the head, side and rear lights and the wiring thereto being arranged in a manner well understood in the art. The switch is here mounted on a base *a* secured to any desired support. A U-shaped plate *b* is secured to the base *a*, the outer ends of the 115 arms being bent inwardly. An angle plate *c* is secured to the forward ends of the two arms, the transverse part of the plate having a bearing for the spindle 13 as in Figs. 1 to 6, while the transverse part of the angle plate has its central portion cut away to form spring arms 11^a with an opening *d* between them in which the detents of the wheel 21 are successively received.

While I have described my invention in 125 connection with a quarter turn switch, it will be obvious that the angular displacement necessary to complete a movement of the switch is determined by the distance apart of the detents on the wheel 21, the 130

number of which detents may, of course, be varied as desired, the pole piece 20 being designed, of course, with reference to the number of detents.

5. In accordance with the provisions of the patent statutes, I have described the principle of operation of my invention, together with the apparatus which I now consider to represent the best embodiment thereof; but 10 I desire to have it understood that the apparatus shown is only illustrative, and that the invention can be carried out by other means.

What I claim as new and desire to secure by Letters Patent of the United States, is:—

15 1. A snap switch mechanism comprising an axially movable rotary member including a switch element and detent means; stop means normally engaging said detent means so as to prevent rotation of said member; a 20 rotary actuator for said rotary member; and means responsive to rotation of said actuator in either direction for exerting tension on said rotary member and shifting said detent means axially to release it from said 25 stop means.

2. A snap switch mechanism comprising a rotary member including a contact plate and axially movable detent and cam means; stop means normally engaging said detent 30 means so as to prevent rotation of said member; a rotary actuator for said rotary member and means forming between said actuator and said member a yielding operating connection adapted to exert tension on the latter in response to rotation of the former in either direction; and means carried by said actuator for coöperating with said cam means to shift said detent means axially to disengage it from said stop means.

3. A snap switch mechanism including an axially movable rotary member comprising a contact plate, a detent wheel, and a double faced cam; means yieldingly resisting axial movement of said rotary member; 45 means normally engaging said detent wheel to prevent rotation thereof in either direction; a rotary actuator for said rotary member; means forming between said actuator and said rotary member a yielding operating connection adapted to exert tension on the latter in response to rotation of the former in either direction; and means carried by the actuator for engaging one or the other of the cam faces in accordance with the direction of rotation of the actuator to move the rotary member axially and release the same from said engaging means.

4. A snap switch mechanism including an axially movable rotary member comprising 60 a contact plate, a star wheel, and a double cam; a spring opposing axial movement of said rotary member; stop means for preventing rotation of said rotary member comprising a pair of yielding members between 65 which one of the detents of the star wheel

is normally held; a rotary actuator for said rotary member facing said cam; means forming between said actuator and said rotary member a yielding operating connection adapted to exert tension on the latter 70 in response to rotation of the former in either direction; and an arm carried by said actuator adapted on such rotation to coöperate with said cam in moving said rotary member axially so as to release the star 75 wheel from said stop means.

5. A snap switch mechanism comprising a rotary member including an axially movable detent wheel; means yieldingly resisting axial movement of said wheel; stop means 80 for preventing rotation of said rotary member comprising a pair of flat springs between which the detents of said wheel are successively received, the upper surfaces of said springs lying in the path of movement 85 of said detents; a rotary actuator for said rotary member comprising means for moving said detent wheel axially to release it from said stop means; and means forming a yielding connection between said actuator 90 and said rotary member adapted to exert tension on the latter in response to rotation of the former.

6. A snap switch mechanism comprising an axially movable rotary member including a detent wheel; means yieldingly resisting axial movement of said rotary member; stop means for preventing rotation of said rotary member comprising a pair of flat springs with their upper surfaces within the 100 path of movement of said wheel; means for exerting tension on said detent wheel and for simultaneously moving it axially against the resistance of said yielding means to free it from said springs, so that the detents of 105 said wheel may successively be brought to rest between said springs by depressing and passing over one of them and engaging another.

7. In a snap switch, a base plate having 110 its ends upturned to constitute brackets, an actuating spindle mounted in one of the brackets, the inner end of which is formed with a projection on either side of the spindle, a sleeve mounted in the other bracket and embracing said spindle, a rotary member loosely mounted on said sleeve and comprising a contact plate, a star wheel, a cam facing the actuator, a tension spring surrounding the inner end of said sleeve and having 120 its ends engaging opposite sides of one of said projections, the other projection engaging said cam, a spring for forcing said rotary member toward the actuator, and stop means for preventing rotation of said rotary member comprising a pair of yielding members 125 between which one of the detents of the star wheel is normally located and from which said detent is released after a predetermined movement of said actuator. 130

8. In a lamp socket, the combination of a key rotatable in either direction, a rotary switch member mounted coaxially with the key, means to lock said rotary member against rotation, a spring connection between said key and said rotary member, and an operative connection between said key and said locking means whereby the rotary member is released after being biased to turn 10 in either direction by corresponding rotation of the key, so as to make a quick make or a quick break and avoid arcing upon making or breaking of circuit.

9. A key socket switch device comprising 15 a key rotatable in either direction; a rotary member inclosed in the socket structure and comprising a switch element and detent

means; spring stop means carried by the socket structure normally engaging said detent means so as to prevent rotation of said rotary member; and yielding means responsive to rotation of said key in either direction for exerting on said rotary member tension tending to rotate it and for releasing the engagement of said detent means and 25 said spring stop means so that said rotary member may rotate until arrested by their reengagement.

In witness whereof, I have hereunto set my hand this 10th day of November, 1913. 30

JOHN R. BYRNE.
